The ornamental design for a gas inlet attachment for wafer processing apparatus, as shown and described.

Aug. 18, 2020 (JP) ..... 2020-017141 D

DESCRIPTION

(51) LOC (13) Cl. **15-09**

FIG. 1 is a front, top and right side perspective view of a gas inlet attachment for wafer processing apparatus showing our new design;

(52) U.S. Cl.

FIG. 2 is a front elevational view thereof;

USPC **D15/144.1**

FIG. 3 is a left side elevational view thereof;

(58) **Field of Classification Search**

FIG. 4 is a right side elevational view thereof;

USPC D13/122, 182, 184, 199; D15/144, D15/144.1, 144.2; D8/2, 382

FIG. 5 is a rear elevational view thereof;

CPC . C23C 16/00; C23C 16/455; C23C 16/45502; C23C 16/45504; C23C 16/45506; C23C

FIG. 6 is a top plan view thereof;

16/45508; C23C 16/4551; C23C

FIG. 7 is a bottom plan view thereof; and,

16/45512; C23C 16/45514; C23C

(Continued)

16/45517; C23C 16/45563; C23C

16/4557; C23C 16/45576; C23C

16/45578; C23C 16/402; C23C 16/4584;

C23C 16/45587; C23C 16/45525; C23C

16/45544; C23C 16/46; C23C 16/45527;

C23C 16/4412; H01L 21/00; H01L 21/02;

FIG. 8 is a cross sectional view taken along line 8-8 in FIG.
4.
